UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A MISS'S PRINCESS COSTUME.

SPECIFICATION forming part of Design No. 14,515, dated December 25, 1883.

Application filed October 27, 1883. Term of patent 3½ years.

To all whom it may concern:

Be it known that I, LOUISE TULLY, of the city, county, and State of New York, have invented and produced a new and original Design for a Pattern of a Miss's Princess Costume, (numbered 8,918;) and I do hereby declare that the engraved prints accompanying this specification convey to any one accustomed to using paper patterns a clear understanding 10 of how a garment made up by the pattern will appear.

The design shows a Princess dress, having a closely-fitted back and closely-fitted fronts, exhibiting buttons from the neck to some distance below the waist-line; a deep front drapery

that displays plaits in its side edges, and a deep slash extending from the bottom at each side, and a full deep back drapery that displays shirrings in the center at the top, plaits in the side edges, and a loopin at the center. Coat-sleeves and a standing collar are added.

What I claim as my invention, and desire to secure by Letters Patent, is—

The design for a miss's Princess costume, as shown in the engraved prints accompanying this specification.

LOUISE TULLY.
